US0D1083742S

(12) **United States Design Patent** (10) **Patent No.:** **US D1,083,742 S**
(45) **Date of Patent:** **** Jul. 15, 2025**

(54) **CANOPY FOR A VEHICLE**

(71) Applicant: **Rock Solid Industries International (Pty) Ltd**, Pietermaritzburgh (ZA)

(72) Inventor: **Michael Voss**, Aledo, TX (US)

(73) Assignee: **Rock Solid Industries International (Pty) Ltd**, Pietermaritzburgh (ZA)

(**) Term: **15 Years**

(21) Appl. No.: **29/902,128**

(22) Filed: **Sep. 8, 2023**

Related U.S. Application Data

(63) Continuation of application No. 29/797,771, filed on Jul. 2, 2021, now Pat. No. Des. 998,534.

(30) **Foreign Application Priority Data**

Jan. 5, 2021 (ZA) A2021/00009

(51) **LOC (15) Cl.** **12-16**

(52) **U.S. Cl.**

USPC **D12/404**
